UNITED STATES PATENT OFFICE.

SALMON THOMPSON AND WILLIAM E. FARRELL, OF MASONVILLE, IOWA.

CAR-SIGNAL.

SPECIFICATION forming part of Letters Patent No. 278,831, dated June 5, 1883.

Application filed July 27, 1882. (No model.)

To all whom it may concern:

Be it known that we, SALMON THOMPSON and W. E. FARRELL, of Masonville, in the county of Delaware and State of Iowa, have invented 5 new and useful Improvements in Alarms for Railroad-Crossings; and we hereby declare that the following is a full, clear, and exact description thereof, reference being had to the accompanying drawings, which form a part of 10 this specification.

The nature of this invention relates to certain new and useful improvements in the construction and operation of devices to insure alarms at railroad-crossings.

15 Wherever roads cross railways it is imperative that the engineer of a train should sound his alarm by whistle or bell before reaching the crossing, and the object of the invention is to insure a certainty in such alarm. It sometimes happens that certain emergencies require the attention of both engineer and firemen at the time when it is necessary to give this alarm, and the adoption of our device will prevent accident arising from such emergencies.

20 Figure 1 is a perspective of a locomotive and section of track, designed to show the operation of our device. Fig. 2 is an enlarged detail, showing the construction of a portion of 30 the device. Fig. 3 is a modification of the construction shown in Fig. 2. Fig. 4 is an end modification, adapted to operate whether the locomotive is going forward or backward.

In the accompanying drawings, A represents 35 a locomotive, and B a section of crossing, and by the side of the track is set the post C, the top of which is provided with the overhanging arm D, to engage with the crank end *a* of the vertical rod E, which is secured to the cab or 40 other suitable portion of the engine in bearings *b*, or any other suitable bearings that will hold this rod in a vertical position and at the same time allow it to rotate freely in bearings. An arm, *c*, as shown in Figs. 2 and 3, or a double arm, *v*, is secured, preferably adjustable, to 45 this rod E, and a wire or rope, *e*, as shown in Figs. 2 and 3, or a double-strand rope, *f*, as shown in Fig. 4, connects the other ends of these arms with the lever which controls the 50 whistle-valve of the engine, as in the rapid motion of the train the concussion produced by the arm D striking the arm *a* is very great and

might destroy the utility of the device; so in the spring *h*, made a portion of this wire or cord, the elasticity of the spring destroys the 55 effect of such sudden concussion, which, turning the rod E to the rear, actuates the whistle, thereby sounding the alarm. After the engine has passed, and the contact between the two arms is broken, means should be provided 60 for returning the rod to its original position, so that its projecting arm *a* should be ready for the next crossing. If a short, quick whistle is all that is required, the rod may be provided with the rigid bail *i*, to which the coil-spring *k* is secured, while the opposite end of 65 said spring is secured to the engine. After the concussion between the arms *D* and *a* has taken place and the contact is broken, the office of this spring would be to rotate the rod back to 70 its original position; and, to insure the stopping of this rotation at the right point, the spring-stop *l* is employed. Where a lengthened alarm is required, a mutilated ratchet, *m*, is secured to the rod, and a similar spring-stop, *l*, already described, but provided with 75 a catch on its extremity, so that it will act as a pawl also, is employed, so that, as the rod is turned in the concussion, the pawl on the end of the stop *l* will engage with one of the teeth, 80 and hold, through the intervening means, the whistle open until the engineer disengages the pawl and pulls the rod back to its position, which is insured by the stop part of the spring *l* engaging with the projection *n* on the ratchet. 85

When it is desired that the device should be so constructed that the alarm will be given with the locomotive running in either direction, the rod should be provided with a double arm, *d*, at each end of which is a two-strand rope, *f*, attached to the spring *h* at one end, while the other end of the spring is attached to the single rope *e*, which controls the action of the whistle, as hereinafter described with relation to the other figures.

We are aware that it has been proposed to give a single blow to a gong by means of a horizontal shaft carrying a vertical arm which is struck by a movable arm attached to a post on the side of the road; but we make no claim to 100 this construction, as it will not give a prolonged whistle, as our invention will.

What we claim as our invention is—

1. In combination with a post, C, carrying the

overhanging arm D, the rod E, provided with the crank-arm *a*, arms *c*, rope *e*, and spring *h*, such rope engaging with the alarm of a locomotive, substantially as specified.

- 5 2. In combination, the rotating rod E, secured to a locomotive, and adapted to be turned by a fixed projection on the side of the road, and provided with a bail, *i*, fast thereon, the returning-spring *k*, the spring-stop *l*, acting on 10 the bail, arm *c*, fast on the rod E, and rope *e*, connected to the whistle-lever, all constructed and arranged to operate substantially as and for the purpose described.
3. In combination with the vertical post C,

carrying the overhanging arm D, the rotating 15 rod E, secured to the locomotive, and provided with a crank-arm, *a*, arm *c*, rope *e*, connecting the arm *c* and the locomotive-whistle, the mutilated ratchet *m*, fast on said rod E, and the spring-pawl stop *l*, acting on the ratchet, all 20 constructed and arranged to operate substantially as and for the purposes set forth.

SALMON THOMPSON.

WILLIAM EDWARD FARRELL.
